UNITED STATES PATENT OFFICE.

B. B. HAWSE, OF MORRISVILLE, VERMONT.

CLOTHES-DRIER.

Specification of Letters Patent No. 26,674, dated January 3, 1860.

To all whom it may concern:

Be it known that I, B. B. HAWSE, of Morrisville, in the county of Lamoille and State of Vermont, have invented a new and useful Improvement in Clothes-Driers; and I do hereby declare that the following is a full, clear, and exact description of the same, reference being had to the annexed drawing, forming part of this specification, in the 10 several figures of which similar characters of reference denote the same part.

Figure 1 is a perspective view of my clothes drier, Fig. 2 is a vertical section of the same on line x, x .

15 The nature of the invention consists in having both hubs perforated, so as to be movable upon the shaft, and having a cord attached to the upper hub passing down around a pulley on the lower hub, and up 20 over a swivel pulley on the head of the shaft, so that this cord performs the double function of elevating the hubs, and expanding the frame. On the lower hub is a self-acting, 25 ratchet eccentric under which the cord passes, which presses it against the hub, and holds it secure so as to fasten the frame firmly at any desired height on the shaft.

In the drawing S, is the shaft, having upon it the two movable hubs H, H'.

30 B, is a band at the head of the shaft to prevent the hubs from slipping off.

C, is the cord attached to the upper hub H', passing around the pulley p , on the lower one H, and over the swivel pulley P, on the 35 head of the shaft, said swivel pulley having a round headed pivot working in a socket in the head of the shaft, allowing it to revolve easily with the frame.

40 R, is the self acting ratchet eccentric on the lower hub H, which presses cord C, against the hub, and holds the frame secure in any desired position on the shaft. So that the cord C, being attached to the upper

hub, and passing over the pulley p , on the lower one as well as over the swivel pulley 45 P, at the head of the shaft, it not only elevates the frame upon the shaft but also expands the frame. And it further may be used to close the frame by drawing the cord above the pulley p , on the lower hub. A 50 knot may be made in the cord which will catch in eye e, on the upper hub, and prevent the frame from coming entirely down on the ground. Therefore when desired to use the drier, by drawing cord C, the frame 55 is expanded, when it can be lowered on the shaft to a convenient position, and the clothes placed on the cords, and by again drawing cord C, the frame can be elevated to any height on the shaft, the self acting, 60 ratchet, eccentric pressing the cord against the hub, and thus securely holding the frame in position on the shaft. This construction is advantageous on account of the frame being raised or lowered to any desired position 65 on the shaft by simply drawing cord C, which also expands the frame and it is well adapted for a drier inside the house, or the frame can be lowered on the shaft, and used to hang the clothes on after ironing. 70

Having thus described my improvement I claim—

Two perforated hubs H, H', movable upon the shaft, in combination with the swivel pulley P, upon the shaft head, cord 75 C, performing the double function of expanding and elevating the frame, and the selfacting ratchet eccentric R, as applied to clothes driers.

In testimony whereof I have hereunto signed my name before two subscribing witnesses.

B. B. HAWSE.
